SPRINKLER

Alfred Netzband and Bruno Kowalski, Berlin-Spandau, Germany

Application February 6, 1934, Serial No. 709,978
In Germany November 25, 1931

8 Claims. (Cl. 299—71)

The present invention relates to rotating sprinklers and it is one of the main objects of the invention to adapt such sprinklers to a more universal use and application than has been possible heretofore.

A further object of the invention is to provide a novel sprinkler of very simple construction which can be manufactured at low costs.

Another object of the invention is the provision of a sprinkler which is quiet and uniform in its operation and which produces a perfectly atomized jet.

Another and very important object of the invention is the provision of a reversing and controlling mechanism on said sprinkler to permit the spraying of any desired sector.

Another object of the invention is to provide a sprinkler having selective means for adjusting the same for continuous uni-directional rotation with or without material atomization of the jet or for permitting alternate movement in opposite directions over any predetermined sector under the control of said reversing mechanism.

Further objects and advantages will be seen from the specification, the claims and the accompanying drawing, which illustrate preferred embodiments of the invention.

Fig. 1 is a side view of a reversible sprinkler which is shown, partly in section.

Fig. 2 is a section on line A—B in Fig. 1.

Fig. 3 illustrates a sprinkler similar to that shown in Fig. 1 but provided with a baffle plate of particular shape.

Fig. 4 is a perspective view of the baffle plate of the sprinkler shown in Fig. 3.

Fig. 5 shows a section through the nozzle of a further embodiment similar to that shown in Figs. 1 and 3 and therefore no sideview thereof is illustrated. The section illustrated in Fig. 5 is taken in said further embodiment on a line just like A—B indicated in Fig. 1 in connection with the embodiment shown in that figure.

Fig. 6 is a fragmentary side elevation of the discharge end of the nozzle showing the rotary element and baffle plate and an adjustable device for controlling the vibrations of the baffle plate.

With reference to Figs. 1 to 3, the nozzle 1 is mounted on the front end of the neck-like member 2 and the nozzle carries on its front end by means of ball bearings 3 the rotary element 4. To the rotary element 4 the baffle plate 5 is rigidly connected which provides the baffle surfaces and which is adapted to rotate around the jet. In the illustrated embodiment, the baffle

plate is screwed to the rotary element and may be adjusted with respect to the jet simply by loosening and retightening the connecting screws, for the water pressure exerted by the jet steadily tends to push aside the baffle plate and thus the same is always kept in its terminal position defined by the more or less loosening or retightening of the said connecting screws as long as the jet is ejecting. In order to permit the baffle plate to adjust itself in the most efficient situation during the operation, the baffle plate may be made resilient; for instance a sheet metal blade may be used having due to its length the necessary resiliency desired for the purpose here in question and in connection therewith causing at the same time a vibrating driving effect as is known per se. In order to confine the range of such self-adjustment to a predetermined rate a set screw 6 in a special support 7 attached to the rotary element 4 may be arranged by the 20 side of the baffle plate.

Into the aforesaid rotary element 4 which is bearing the baffle plate is screwed a stop pin 8 adapted to selectively establish an operative connection between the baffle plate and the neck member 2, so that the nozzle mechanism will perform a uni-directional rotary movement. The outer end of the said stop pin is adapted to engage on its path the cams 9, 10 of a stop disk 11 tiltably mounted upon said nozzle. Said diametrically arranged cams 9, 10 serve to reverse the rotary movement of the necklike member 2 of the sprinkler as will be hereinafter described. Said stop disk 11 is also provided with a control lever 12 and is mounted on said nozzle at 13 and 14 so as to be tilttable about an axis defined by the screws 13 and 14. The control lever 12 extends downwardly from the stop-disk and passes between two stops 15, 16 on the stationary part of the sprinkler. Each of said stops is fastened in a ring member rotatably adjustable on the stand of the sprinkler.

The sprinkler operates as follows:

The water jet issuing from the nozzle impinges with its outer layers of water upon the baffle surface of the baffle plate 5; thereby the outer sleeve of the jet is atomized and the rotary element 4 on the other hand is set in rotation by reaction. A water spray jacket is thus produced around a core jet. In the example illustrated, the stop-pin 8 at the periphery of the rotary element will engage one of the cams 9, 10, for instance the cam 9 thereby preventing further rotation of the element 4, while the baffle plate is then held stationary, the water reaction will be transmitted through the stop pins 8 and the stop disk 11 to

the sprinkler. Due to the relative position of the stop pin *e* and the cam *d* with respect to the baffle surface, the reaction will act transversely to the axis of rotation of the rotary element and the member *2* is set in rotation until its movement is prevented or until the rotary element is again released for rotation. In the example illustrated the release is effected when the control lever strikes the stop *f*. The pressure the stop *f* exerts on the control lever causes a tilting movement of the stop disk *b* on the nozzle *1*; thereby the cam *d* is withdrawn from the stop pin *e* and the rotary element *h* can continue its rotary movement about the jet in the same rotary direction as before. However upon withdrawal of the cam *d* caused by the tilting movement of the stop disk, the opposite cam *d*₁ has been advanced at the same time, when the first-mentioned cam was withdrawn and after one half revolution the rotary element is newly stopped, the said opposite cam *d*₁ engaging the stop-pin *e*. Since the baffle surfaces now are stationary again, the water reaction will cause an opposite rotation of the sprinkler, which again will continue until the control lever *c* encounters again a fixed stop provided on the stand of the sprinkler. If only one stop *f* is provided, the rotating movement of the sprinkler reverses always after one full revolution. In the example illustrated two spaced stops *f*, *f*₁ are arranged and the said two stops alternately cause a reversing movement, thus the angle or sector to be sprayed is determined by the space left between the two stops. The adjustability of the two stops in the illustrated embodiment permits to select said sector as large as desired and to displace said sector without turning of the sprinkler. By special construction of the baffle sheet, for instance such as shown in Figs. 3 and 4, it is possible to produce adjacent the jet proper a water fan, which causes spraying of a rectangular area as will be described in connection with the said Figs. 3 and 4.

From the drawing it may be seen, that even
sprinklers already in use can be provided without
difficulty with a rotatable element having atom-
izing baffle surfaces or such sprinklers may
be converted into reversing sprinklers by provid-
ing thereon the reversing device herein described.

With reference to Figs. 3 and 4 the baffle plate 50 is provided with perforated lugs or lips u , u' serving for fastening the baffle plate on the rotatable element. At the end of the baffle plate a opposite the afore said lugs extends a propeller surface 13 beyond the reaction surface proper indicated at 11 , and adjacent the latter a cylindrical guide surface 12 is arranged.

The various surfaces cooperate in the following manner:

The cylindrical guide surface 12 forces the jet 60 against the reaction surface proper 11 and insures a continuous effective impact on the latter. At the same time the water impinging the guide surface 12 establishes in connection with the same an injector-like suction action and prevents the 65 dripping of water from the nozzle mouth. The propeller surface extending beyond the front end of the baffle surface proper strengthens the reaction effect, and at the same time produces a special water fan extending sidewardly and rearwardly towards the sprinkler and completing thereby the sector directly sprinkled by the same into a rectangle thus causing a uniform irrigation of the entire surface swept by the sprinkler including the area immediately adjacent its 70 stand. The steady and uniform operation of the 75

sprinkler may be improved by the provision of a counter weight of fly mass 14, preferably provided on the rotary mechanism diametrically opposite the jet, as clearly shown in Fig. 3 of the accompanying drawing.

A perfect operation of the sprinkler in swiveling and reversing action as well as in spraying and atomizing effect is obtained, if the axis of rotation of the idle-running rotary element is coaxial to the axis of the jet. As long as the nozzle mouth is truly circular and the axis of rotation of the rotary member h and its associated baffle plate coincides with the axis of the jet issuing from the nozzle mouth, the impact exerted upon the baffle plate by the jet will be practically uniform throughout the entire cycle of rotation of the baffle around the jet and, in the absence of a positive connection between the rotary element h and the member 2 such as the connection effected by the stop-pin e and cams d , d_1 , there will be no reaction exerted on the neck member 2 tending to rotate the same about its axis. If, however, there is some small eccentricity between the axis of rotation of the member h and its associated baffle plate with respect to the axis of the jet, for instance if the nozzle mouth is simply made unround on one side on a substantially horizontal plane as indicated in Fig. 5, this unround portion or eccentricity, coupled with the intermittent shaking or vibrating impulses produced by the rotation of the member h and baffle plate around the jet, is sufficient to cause a reaction of the jet upon the member 2 thereby causing rotation of the latter while the baffle plate is rotating around the jet atomizing the outer layers thereof. In this case no means for establishing an operative connection between the said baffle plate and the rotary neck member 2 are needed unless a reversing action is desired. While the mere eccentricity of the nozzle mouth or of the nozzle axis, would not, of itself, produce the necessary directional force to effect the rotation of the member 2 , the successful operation of the sprinkler is based upon the conception that intermittent shaking or vibrating impulses such as those produced by the rotation of the member h and its associated baffle plate, cause a reduction of the friction in the bearing of the rotating head or nozzle mechanism of the sprinkler in such a manner that even the slightest torque impulses are sufficient to cause a rotation of the entire sprinkler mechanism.

While there have been shown and described and pointed out various preferred embodiments of the invention, it will be understood that many changes in the construction and details of the novel device may be provided by those skilled in the art without departing from the spirit of the invention.

What we claim is:

1. In a sprinkler, a rotary nozzle mechanism through which the jet is ejected, a rotatable element arranged at the mouth of the nozzle and mounted on the rotary nozzle mechanism, a baffle plate connected to said rotatable element and adapted to drive the latter, said baffle plate having a reaction surface continuing in the direction of the jet in a propelling surface and continuing sidewardly in the direction of the rotation of the rotatable element in a cylindrical guiding surface for the jet, said baffle plate arranged to embrace and be impacted by said jet, and means for periodically transmitting the reaction from the reaction surface of the baffle to the rotary nozzle 78

mechanism in a direction to cause alternate rotation of said rotary nozzle mechanism.

2. A sprinkler as specified in claim 1, wherein a fly mass is connected to said rotary mechanism, 5 said fly mass being preferably provided on the rotary mechanism diametrically opposite the jet.

3. In a sprinkler, a rotary nozzle mechanism through which the jet is ejected, a rotatable element on the rotary nozzle mechanism, a baffle 10 plate connected to said rotatable element having a reaction surface arranged to embrace and be impacted by the jet and adapted to drive the rotatable element, the rotary element being arranged coaxially to the jet, and means for periodically transmitting the reaction from the 15 reaction surface of the baffle to the rotary nozzle mechanism in a direction to cause alternate rotation of said rotary nozzle mechanism.

4. In a sprinkler, a rotary nozzle mechanism 20 through which the jet is ejected, a rotatably mounted element arranged to embrace said jet, a baffle plate mounted on said rotatably mounted element and having a reaction surface arranged to embrace and be impacted by said jet to cause 25 rotation of said rotatably mounted element, said rotatably mounted element and baffle plate being mounted at the mouth of the rotary nozzle mechanism, and means for periodically transmitting the reaction from the reaction surface 30 of the baffle to the rotary nozzle mechanism in a direction to cause alternate rotation of said rotary nozzle mechanism.

5. A sprinkler as specified in claim 4 having a resilient baffle plate.

6. In a sprinkler, a rotary nozzle mechanism through which the jet is ejected, a rotatable element arranged at the mouth of the nozzle and mounted on the rotary nozzle mechanism, a baffle plate connected to said rotatable element 35 having a reaction surface arranged to embrace and be impacted by said jet and adapted to drive

the rotatable element, and means for periodically holding said rotary element stationary with respect to said rotating nozzle mechanism to periodically transmit the reaction from the reaction surface of the baffle to the rotary nozzle mechanism in a direction to cause alternate rotation of said rotary nozzle. 5

7. In a sprinkler, a rotary nozzle mechanism through which the jet is ejected, a rotatable element arranged at the mouth of the nozzle and 10 mounted on the rotary nozzle mechanism, a baffle plate connected to said rotatable element having a reaction surface arranged to embrace and be impacted by the jet and adapted to drive the rotatable element, a stop pin projecting from 15 said rotatable element, a controlling means tiltably mounted on said nozzle mechanism and provided with two cams arranged in opposite positions and arranged to be brought into the path of the stop pin on the aforesaid rotatable element to arrest the same alternately in one of two opposite positions in each of which positions the reaction surface of the baffle is positioned to receive a lateral impact to effect rotation of the 20 nozzle mechanism in opposite direction, said cams 25 being alternately advanced into the path of said stop pin upon alternate tilting movements of the controlling means, and stationary stop means arranged to control the said alternate tilting movements of said controlling means. 30

8. A sprinkler as specified in claim 7, wherein said stop means arranged to control the alternate tilting movements of said controlling means comprises two stop pins arranged to engage a controlling lever connected to said tiltably mounted 35 means, each stop pin being fastened on a ring adjustably arranged on a stationary tubular support carrying said rotary nozzle mechanism.
